US00D733649S

(12) **United States Design Patent**
Behar et al.

(10) **Patent No.:** US D733,649 S
(45) **Date of Patent:** ** Jul. 7, 2015

(54) **DISPLAY FOR ELECTRONIC DEVICE**

(71) Applicant: **General Electric Company**,
Schenectady, NY (US)

(72) Inventors: **Yves Albert Behar**, San Francisco, CA
(US); **Joshua Tree Morenstein**, San
Francisco, CA (US); **Pichaya
Puttornkul**, San Francisco, CA (US);
Matthew David Swinton, San
Francisco, CA (US); **Jennifer Yoko
Olson**, San Francisco, CA (US);
Matthew John Malone, San Francisco,
CA (US)

(73) Assignee: **GENERAL ELECTRIC COMPANY**,
Schenectady, NY (US)

(**) Term: **14 Years**

(21) Appl. No.: **29/510,812**

(22) Filed: **Dec. 3, 2014**

Related U.S. Application Data

(60) Division of application No. 29/464,589, filed on Aug.
19, 2013, which is a continuation of application No.
29/383,179, filed on Jan. 13, 2011, now Pat. No. Des.
688,199.

(57) **CLAIM**

We claim, the ornamental design for an display for electronic
device, as shown and described.

DESCRIPTION

FIG. 1 is a perspective view of a first embodiment the invention;

FIG. 2 is a front view of the embodiment of FIG. 1;

FIG. 3 is a rear view of the embodiment of FIG. 1;

FIG. 4 is a side view of the embodiment of FIG. 1, the
opposite side being a mirror image thereof;

FIG. 5 is a top view of the embodiment of FIG. 1; and,

FIG. 6 is a bottom view of the embodiment of FIG. 1.

The broken lines shown in FIG. 1-FIG. 6 are environmental
and not part of the claimed design.

References to “side”, “top”, “front”, “rear” and “bottom” in
the figure descriptions are not meant to require certain in-use
orientation; a display for electronic device according to the
claimed design may be used in any orientation.

1 Claim, 5 Drawing Sheets
